UNITED STATES PATENT OFFICE

NELLIE B. HUSSEY, OF PEKING, CHINA

DESIGN FOR A LADY'S HAND BAG

Application filed June 27, 1930. Serial No. 36,199. Term of patent 14 years.

To all whom it may concern:

Be it known that I, NELLIE B. HUSSEY, a citizen of the Dominion of Canada, residing at Peking, China, have invented a new, original, and ornamental Design for Lady's Hand Bag, of which the following is a specification, reference being had to the accompanying drawing, forming part thereof.

Fig. 1 of the drawings is a plan view showing my new design.

Fig. 2 is a side elevation.

Fig. 3 is an end elevation.

I claim:

The ornamental design for a lady's handbag, substantially as shown.

NELLIE B. HUSSEY.
